MASSAGE MACHINE

William N. Moxley, 3821 Don Tomaso Drive,
Los Angeles 8, Calif.

Filed July 25, 1957, Ser. No. 674,103

6 Claims. (Cl. 310—63)

The present invention relates to machines or apparatus for imparting a mechanical massaging action to different regions of a person's body.

An object of the invention is to provide a massage machine for imparting a mechanical massaging action to a person's body, which has a smooth and consistent operation, is capable of withstanding substantial loads over long periods, and is relatively quiet while in operation.

Another object of the invention is to provide an electric motor operated massage machine for imparting a mechanical massaging action to a person's body, in which the motor does not overheat, remaining in a comparatively cool state, despite continuous use of the machine over extended periods and under comparatively heavy load conditions.

A further object of the invention is to provide an electric motor operated massage machine for imparting a mechanical massaging action to a person's body, the motor having a smooth and quiet operation, being of strong and sturdy construction, and comparatively economical to manufacture.

This invention possesses many other advantages, and has other objects which may be made more clearly apparent from a consideration of a form in which it may be embodied. This form is shown in the drawings accompanying and forming part of the present specification. It will now be described in detail, for the purpose of illustrating the general principles of the invention; but it is to be understood that such detailed description is not to be taken in a limiting sense, since the scope of the invention is best defined by the appended claims.

Referring to the drawings:

Figure 1 is a longitudinal section, with parts shown in elevation, through a massage machine embodying the invention;

Fig. 2 is a cross-section taken along the line 2—2 on Fig. 1;

Fig. 3 is a cross-section taken along the line 3—3 on Fig. 1;

Fig. 4 is a section taken along the line 4—4 on Fig. 1;

Fig. 5 is a cross-section taken along the line 5—5 on Fig. 1;

Fig. 6 is a section taken along the line 6—6 on Fig. 1;

Fig. 7 is an exploded isometric projection of the motor casing or housing;

Fig. 8 is an isometric projection of one of the bearing cushioning members.

The massage machine shown in the drawings is particularly adapted for application, either directly or indirectly, to parts of a person's body for the purpose of imparting a massaging action thereto. The machine may be applied directly to the person's body, or may be incorporated in other apparatus or devices to impart its massaging action therethrough to the person's body. Examples of such other devices are pillows, in which the massage machine is contained, different parts of a person's body being adapted to bear or rest upon the pillow; and chairs in which a person may be seated or recline,

2

a massaging action being transmitted from the machine, through the different parts of the chair, to the various areas of the person's body. The particular machine illustrated does not impose merely a straight line vibratory motion to the person's body, but more in the nature of a circular or gyratory motion, so as to actually impart a generally circular massaging action to the various regions of the person's body.

The massage machine includes an electric motor 10. Extending from one end of the motor casing 11 is an armature or rotor shaft 12, the extended portion 13 of which is preferably square in cross-section and fits snugly through a companion square bore in an eccentric 14 having the desired degree of eccentricity or throw. The eccentric is preferably made of a synthetic resin, so that it can be forced upon the armature shaft 13 to provide a snug fit therewith. Because of its characteristics, the synthetic resin eccentric 14 minimizes the generation and transmission of sound. It has been found that the making of the eccentric of synthetic resin reduces the noise level of the massage machine to a considerable extent without adversely affecting its operation.

The eccentric 14 is retained upon the armature shaft 13 against endwise displacement therealong in any suitable manner, as by means of a cotter pin 15 adjacent the outer end of the eccentric and extending through the armature shaft.

Surrounding the eccentric 14 is an inner race 16 of a radial type of rollable bearing 17 around which ride ball bearing elements 18. These elements, in turn, ride upon an outer race 19 surrounding the bearing elements and the inner race 16. This outer race is disposed within a bearing support 20 encompassing the entire bearing structure 17, the outer race 19 being secured to the bearing support against rotation through the intermediary of a rubber or rubber-like cushion member 21 which includes a base portion 22 engaging a transverse shoulder 23 of the bearing support and a plurality of circumferentially spaced rubber fingers or segments 24 surrounding the outer race. The rubber-like cushion member 21 will permit some relative gyratory motion to occur between the bearing support 20 and the bearing 17, eccentric 14, and shaft 12 disposed therewithin.

The bearing support 20 actually forms one end of a main frame 25 through which the massaging action, resulting from the rotation of the eccentric 14, is transmitted. Extending substantially radially from the bearing support 20 is an arm 26 integral therewith, or otherwise suitably secured thereto, the outer end of this arm being integral with, or otherwise suitably secured to, a base or shoe plate 27 extending to one side of or generally lengthwise of the electric motor 10 to its opposite end. The other end of the shoe plate is integral with, or is suitably secured to, another generally radial arm 28 which extends inwardly toward the axis of the massage machine, the inner portion of this arm being integral with a cross-piece or bar 29, to which the rear end of the electric motor casing 11 is attached through the agency of a flexible connection or coupling 30. Extending generally radially from the cross-piece or bar is an arm extension 31 integral therewith.

The flexible connection or coupling 30 will permit the left-hand or rear portion of the electric motor 10 and of the main frame 25 to have a relative gyratory or universal motion, to permit appropriate operation of the rotatable eccentric 14 in imparting a circular or gyratory action to the main frame 25 of the machine. As specifically disclosed, the flexible coupling 30 includes a plate 32, preferably made of a fibrous material, disposed in a plane substantially parallel to the motor axis. The fibrous or flexible plate of a suitable thickness includes a body portion 33 extending across and bearing against

the inner surface 29a of the cross-piece or bar 29. For the purpose of increasing the bearing area of the plate against the cross-piece or bar and the effective cross-section of the flexible plate itself, so as to better withstand the gyratory action, the arm extension 31 has a groove 34 to permit the body portion 33 of the flexible plate to be disposed under the extension against a greater area of surface of the cross-piece 29. Disposed on opposite sides of the arm extension are a pair of outer arms 35 of the plate that lie snugly against the sides of the extension 31. These arms have holes therethrough through which screws 36 may pass into companion threaded holes in the cross-piece 29, the heads of the screws preferably bearing against washers 37 engaging the outer surface of the plate 32, to firmly secure the flexible plate to the cross-piece or bar 29.

The inner portion of the flexible plate 32 is disposed within or under a transverse flange 38 integral with and extending axially of the rear end wall 39 of the motor housing or casing 11. This flange 38 lies substantially parallel to the surface 29a of the cross-piece or bar 29, and bears against the flexible plate 32. The latter plate is firmly secured to the motor housing flange 38 by bolts 40 extending through holes in the flange and flexible plate, the heads 41 of the bolts bearing against washers 42 engaging the outer surface of the flange 38, while nuts 43 threaded on the bolts may bear against washers 44 engaging the opposed surface of the flexible plate, thereby clamping the plate 32 firmly against the inner surface of the transverse flange 38.

As the electric motor shaft 12 rotates, the eccentric 14 imposes a gyratory action to the right or forward end of the main frame 11, in which the eccentric 14, bearing 17, and rubber cushioning member 21 are carried. During such eccentric rotation, the flexible plate 32 deflects to a sufficient extent to permit the gyratory action to occur. The flexible plate may be made of fiber, leather, or similar material. In view of its arrangement and coaction with the motor housing 11 and the arm 28 of the main frame of the apparatus, it possesses a long and effective life without breakage or tearing.

The massage action, due to the rotating eccentric 14, is imparted to a cup-shaped closure member 45, the skirt portion 46 of which is adapted to slide and fit snugly over the bearing support 20, this skirt having a notch or groove 47 in which the radial arm 26 of the main support or frame 25 can extend. This cup-shaped member is secured to the bearing support 20 by circumferentially spaced screws 48. The gyratory or massaging action imparted by the eccentric 14 to the bearing support 20 is transmitted to this cup-shaped member 45, which preferably has an end wall 49 so that other devices (not shown), such as rubber members, may be fitted readily thereover for application to different parts of a person's body, the massaging action being transmitted through such other devices to the desired region or regions of the person's body.

A cup-shaped closure member 50 is also provided at the other or rear end of the main frame, this cup-shaped member fitting snugly over the outer end of the arm extension 31 and around the outer circular surfaces of the cross-piece or bar 29. This cup-shaped member 50 also is provided with a notch or groove 51 through which the radial arm 28 can pass, and it is firmly secured to the arm structure 28, 29, 31 by screws 52 threaded into the extension and cross-piece. The end wall 53 of the closure member has a bushing 54 therein through which an electric line or cord 55 passes, which runs to the electric motor 10 for the purpose of delivering the required current thereto.

The electric motor is of a strong and sturdy construction, being comparatively economical to manufacture, and maintained in a cool state over extended periods, despite the imposition of relatively heavy loads thereon. As illustrated, it includes the casing or housing 11, which

is made in two opposed sections 60, 61. The forward section has a longitudinally extending wall 62 integral with a forward end wall 63, through which the armature or rotor shaft 12 extends. The rearward section 61 also has a longitudinally extending wall 64 integral with the rear end wall 39, which supports the rear end of the armature or rotor shaft 12, and which is also integral with the transverse flange 38 to which the flexible plate 32 is secured.

10 The motor rotor or armature 65 is attached in any suitable manner to the shaft 12, the forward end of the armature engaging a cooling fan 66 having circumferentially spaced blades 67 thereon, the shaft extending through an anti-friction bearing 68 mounted in the forward end wall 63 of the housing. The inner race 69 of the anti-friction bearing snugly fits the armature shaft 12, there being balls 70 rollable on the inner race which, in turn, engage an outer race 71 received within a rubber or rubber-like cushioning member 72, of the same type 15 as the cushioning member 21 in which the eccentric bearing 17 is mounted. Thus, the cushioning member 72 includes a base portion 73 engaging a transverse shoulder 74 in the end wall 63 and circumferentially spaced fingers or buttons 75 disposed around the outer race 71 20 and engaging the inner cylindrical wall of the bearing support 76 provided by the forward end wall 63.

Longitudinal movement of the rotor shaft 12 and the rotor 65 in a forward direction is prevented by engagement of a shoulder 77 on the shaft with the inner race 30 69 of the forward anti-friction bearing. The rear portion of the armature shaft is rotatably mounted in a rear anti-friction bearing 78 substantially the same as the forward anti-friction bearing. The shoulder 79 at the rear portion of the armature or rotor shaft engages this 35 antifriction bearing 78, which also bears against the base portion 80 of a rubber cushion member that engages a transverse shoulder 81 of the rear end wall 39 of the housing. The outer race of the rear bearing 78 also engages and is encompassed by circumferentially spaced fingers or button members 82 integral with the base portion 80 of the cushion member that fits snugly within the cylindrical wall of the rear bearing support 83 which is integral with the end wall 39 of the rearward housing section 61.

40 The stator 85 of the motor surrounds the rotor 65 and is disposed in both the forward and rearward sections of the housing. It is located appropriately lengthwise of the housing by having its forward end 86 engage shoulders 87 provided in the longitudinal wall 62 of the forward section 60. The stator is prevented from moving in a rearward direction with respect to the housing by virtue of a pair of spacer sleeves 88, a plate 89 for supporting the brushes 90 of the electric motor, and a pair of threaded sleeves 91. As disclosed, the forward 45 ends of the spacer sleeves 88 engage the rear end of the stator 85, the plate 89 engaging the rear ends of the spacer sleeves, and the threaded sleeves 91 engaging the rear side of the brush holder plate 89. The end wall 39 of the rearward housing or casing section engages the rear end of each threaded sleeve 91. A plurality of relatively long screws 92 is inserted through holes 93 in the forward wall 63 of the housing, these screws passing through longitudinally extending holes 95 in the stator 85, through the spacer sleeves 88 and the brush holding plate 89, with the threaded ends of the screws threaded into the threaded sleeves 91. The heads 96 of the screws are disposed in recesses 97 and engage the base of said recesses or counterbores when 50 the screws 92 are tightened. The rearward section 61 of the housing is secured to the forward section 60 by relatively short screws 98 inserted through holes 99 in the rear end wall 39 of the motor casing, and threaded into the threaded sleeves 91. When tightened, the heads 55 99 of the screws are disposed in recesses or counterbores

60 65 70 75

100 in the end wall 39 and engage the bases of such recesses.

By virtue of the construction described, the screws 92, 97, spacer sleeves 88, brush supporting plate 89, and threaded sleeves 91, coupled with the engagement of the stator 85 with the shoulder 87 formed on the forward housing section 60, hold the stationary parts of the motor in assembled relation. The stator 85 cannot move forwardly by virtue of its engagement with the shoulder 87 and cannot move rearwardly by virtue of its engagement with the spacer sleeves 88, tightening of the screws 92 clamping the stator 85, spacer sleeves 88, brush plate 89, and threaded sleeves 91 against one another. Tightening of the screws 97 will secure the ends of the forward and rearward housing sections 60, 61 in abutment with one another.

The rotor or armature shaft 12 has a commutator 101 mounted on its rear portion, and this commutator is engaged by carbon or other brushes 90 that are slideable in holders 102 secured to the supporting plate 89. Springs (not shown), or the like, are disposed in the holders to constantly urge the brushes 90 against the commutator 101. The current is fed to the brushes and to the stator in the usual manner from the electric line 55.

For the purpose of maintaining the massage unit and its motor in a comparatively cool state during extended periods of operation, provision is made for circulating substantial quantities of air through the electric motor 10. In addition, large radiation surfaces are provided to dissipate the heat produced in the motor. As disclosed, the exterior of the casing or housing 11 is provided with a plurality of longitudinal grooves 105 extending substantially throughout the length of the casing, which define cooling fins or ribs 106 therebetween. Air circulating around such fins or ribs 106 will remove heat therefrom, this heat being drawn from the interior of the motor casing 11, through the casing wall itself. For the purpose of facilitating the holding of the electric motor in the hand of a person during its use in performing a massaging action on the person's body, the casing is provided with longitudinally extending finger recesses 107 on opposite sides of the casing. These finger recesses 107 also increase the area to be contacted by ambient air for the purpose of effecting cooling of the motor.

Air is also circulated through the motor during its rotation by the cooling fan 66. A substantial number of circumferentially spaced holes 108 is provided in each end wall 63, 39 of the housing 11, the air being drawn through one set of holes, passing through the motor and being discharged through the other set of holes. Such air will not only pass between the rotor 65 and the stator 85, but it is also caused to circulate around the exterior of the stator and along the longitudinal walls of both the forward and rearward sections 60, 61 of the casing. It is to be noted that the interior of the longitudinally extending walls of the casing is provided with circumferentially spaced air passages, grooves, or flutes 109, through which air can flow from one end of the casing to the other and around the stator 85. Such air will not only cool the casing 11, but it will also more effectively cool the stator and the rotor, drawing the heated air from these parts.

The circulation of air through the apparatus is further enhanced by providing circumferentially spaced holes or ports 110 in the end walls 49, 53 of the cup-shaped members 45, 50. Thus, the air discharged through the holes 108 in the rear end wall 39 can pass laterally out through the space between the cup-shaped member 50 and the end wall 39, as well as through the cup-shaped member and out through the holes 110 in the end wall of the rear cup-shaped member.

It is, accordingly, apparent that a massage machine has been provided which will have a smooth, quiet operation because of the several ball bearing constructions

and the cushioning members provided in connection therewith. The motor will be maintained in a comparatively cool state, despite continued use over extended periods and under heavy load conditions, since a relatively large quantity of air is circulated through the motor casing and around its several parts. Ambient air can also contact the exterior of the motor casing and remove air therefrom. In this connection, the casing may be made of aluminum, in order to secure a rapid dissipation of the heat generated in the apparatus. The apparatus is easy to assemble, the parts being accurately positioned with respect to one another, and being held in assembled relation in a relatively simple manner, as, for example, through the simple expedient of the plurality of screws, the spacer sleeves, and the threaded sleeves.

The inventor claims:

1. In a massage machine: a frame having a base and spaced arms extending inwardly from said base; an electric motor between said arms extending lengthwise of said base, said motor including a casing having forward and rearward end walls, a stator secured in said casing, a rotor, a shaft secured to said rotor and having a portion extending through said forward wall, a bearing on said shaft at each end wall, a pliant, elastic means engaging each bearing and end wall and disposed circumferentially around said bearing and between an end of said bearing and said end wall; eccentric means connecting said extending portion of said shaft to one of said arms; a flexible connection between said rearward wall and the other of said arms; said end walls having holes therethrough; said casing having longitudinally extending grooves in its inner wall disposed outwardly of said stator; and means for circulating air from the exterior of said motor through the holes in one end wall, through said grooves in contact with said casing and the holes in the other end wall to the exterior of said motor.
2. In a massage machine: a frame having a base and spaced arms extending inwardly from said base; an electric motor between said arms extending lengthwise of said base, said motor including a casing having forward and rearward end walls, a stator secured in said casing, a rotor, a shaft secured to said rotor and having a portion extending through said forward wall, a bearing on said shaft at each end wall, a pliant, elastic means engaging each bearing and end wall and disposed circumferentially around said bearing and between an end of said bearing and said end wall; eccentric means connecting said shaft portion to one of said arms; a flexible connection between said rearward wall and the other of said arms; said end walls having holes therethrough; said casing having longitudinally extending grooves in its inner wall disposed outwardly of said stator; means for circulating air from the exterior of said motor through the holes in one end wall, through said grooves in contact with said casing and the holes in the other end wall to the exterior of said motor; said casing having external longitudinally extending grooves therein for increasing the cooling surface of said casing.
3. In a massage machine: a frame having a base and spaced arms extending inwardly from said base; an electric motor between said arms extending lengthwise of said base, said motor including opposed forward and rearward casing sections abutting one another, said forward section having a forward end wall and said rearward section having a rearward end wall, one of said sections having a shoulder therein, a stator in said casing sections engaging said shoulder, threaded fastening means extending through said stator and casing sections and common to said stator and casing sections to secure said sections together and said stator against said shoulder, a rotor, a shaft secured to said rotor and rotatably mounted in said end walls and having a portion extending through said forward wall; eccentric means connecting said shaft portion to one of said arms; a flexible

connection between said rearward wall and the other of said arms; said end walls having holes therethrough; said forward and rearward casing sections having aligned longitudinally extending grooves in their inner walls disposed outwardly of said stator; and means for circulating air from the exterior of said motor through the holes in one end wall, through said grooves in contact with said casing and the holes in the other end wall to the exterior of said motor.

4. In a massage machine: a frame having a base and spaced arms extending inwardly from said base; an electric motor between said arms extending lengthwise of said base, said motor including opposed forward and rearward casing sections abutting one another, said forward section having a forward end wall and said rearward section having a rearward end wall, one of said sections having a shoulder therein, a stator in said casing sections engaging said shoulder, threaded fastening means extending through said stator and casing sections and common to said stator and casing sections to secure said sections together and said stator against said shoulder, a rotor, a shaft secured to said rotor and having a portion extending through said forward wall, a bearing on said shaft at each end wall, a pliant, elastic means engaging each bearing and end wall and disposed circumferentially around said bearing and between an end of said bearing and said end wall; eccentric means connecting said shaft portion to one of said arms; a flexible connection between said rearward wall and the other of said arms; said end walls having holes therethrough; said casing sections having aligned longitudinally extending grooves in their inner walls disposed outwardly of said stator; and means for circulating air from the exterior of said motor through the holes in one end wall, through said grooves in contact with said casing and the holes in the other end wall to exterior of said motor.

5. In a massage machine: a frame having a base and spaced arms extending inwardly from said base; an electric motor between said arms extending lengthwise of said base, said motor including opposed forward and rearward casing sections abutting one another, said forward section having a forward end wall and said rearward section having a rearward end wall, one of said sections having a shoulder therein, a stator in said casing sections engaging said shoulder, threaded fastening means extending through said stator and casing sections and common to said stator and casing sections to secure said sections together and said stator against said shoulder, a rotor, a shaft secured to said rotor and having a portion extending through said forward wall, a bearing on said shaft at each end wall, a pliant, elastic means engaging each bearing and end wall and disposed circum-

ferentially around said bearing and between an end of said bearing and said end wall; eccentric means connecting said shaft portion to one of said arms; a flexible connection between said rearward wall and the other of said arms; said end walls having holes therethrough; said casing sections having aligned longitudinally extending grooves in their inner walls disposed outwardly of said stator; means for circulating air from the exterior of said motor through the holes in one end wall, through said grooves in contact with said casing and the holes in the other end wall to the exterior of said motor; said casing sections having external longitudinally extending grooves therein for increasing the cooling surface of said casing.

6. In a massage machine: a frame having a base and spaced arms extending inwardly from said base; an electric motor between said arms extending lengthwise of said base, said motor including a casing having forward and rearward end walls, a stator secured in said casing, a rotor, a shaft secured to said rotor and having a portion extending through said forward wall, a bearing on said shaft at each end wall, a pliant, elastic cushioning member between each bearing and adjacent end wall and including a base portion engaging an end of said bearing and adjacent end wall and circumferentially spaced buttons disposed around said bearing and engaging said bearing and adjacent end wall; eccentric means connecting said extending portion of said shaft to one of said arms; a flexible connection between said rearward wall and the other of said arms, said end walls having holes therethrough; said casing having longitudinally extending grooves in its inner wall disposed outwardly of said stator; and means for circulating air from the exterior of said motor through the holes in one end wall, through said grooves in contact with said casing and the holes in the other end wall to the exterior of said motor.
